GREENLEAF WHITTIER PICKARD, OF NEWTON CENTER, MASSACHUSETTS, ASSIGNOR
TO WIRELESS SPECIALTY APPARATUS COMPANY, OF BOSTON, MASSACHUSETTS, A
CORPORATION OF NEW YORK

PHONOGRAPHIC MACHINE

Application filed December 5, 1922. Serial No. 605,132.

This invention relates to improvements in phonographic machines whereby they are adapted to operation either by the phonographic record or by telephonic means such as the telephone receiver of the receiving set of a radio broadcasting system.

The object of the invention is to simplify such apparatus and make them more efficient.

The invention consists of the arrangement shown in the drawings, of which

Figure 1 is an elevation, partly in section, of that part of a phonographic machine comprising the tone arm and the sound producer;

Fig. 2 is an end view of the same;

Fig. 3 is an elevation, partly in section, of another embodiment of the invention; and

Fig. 4 is a view, partly diagrammatic, illustrating another embodiment.

Fig. 4 shows the apparatus described in the application of George S. Davis, Serial Number 532,227, filed 27 January 1922, on pages 12 and 13, beginning at the fourth line from the bottom of page 12 and including the seventeenth line of page 13. In Fig. 4, the phonograph reproducing lever RL is modified at or near its pivoted portion at P, so that that portion assumes the form of an armature A of an electromagnetic telephone receiver (preferably polarized in the ordinary way by permanent magnet N), this telephone being provided with windings W¹, W² adapted to be connected with the line RR, RR or a radio receiving set. When desired to change from phonographic use to telephone use, the

reproducer, including reproducing lever RL and diafragm D to which it is connected, is moved to move needle N from the phonograph record or table, whereupon the telephone circuit is connected up and operates

the same reproducer diafragm D as does the needle, the sound being amplified by the ordinary sound amplifying apparatus of the phonograph. The telephone winding W¹, W² is such that telephone currents produce such varying magnetic fluxes between the magnet pole pieces O¹, O² and armature A that the latter oscillates on its pivot P in the same way in which it oscillates when actuated by the phonograph needle N, i. e., the telephone winding is such as to exert a torque

on the pivoted armature according to construction and operation as well known to telephone engineers.

In Fig. 3 is illustrated the combination with a phonographic machine of a so-called Baldwin type of telephone having a fairly heavy mica diafragm D. Here, as in Fig. 4, diafragm D is common to both the phonograph reproducer and the telephone receiver (in Fig. 4 reproducing lever RL constitutes the connection between telephone armature A and diafragm D). In Fig. 3, telephone armature A is independent of reproducing lever RL, and is pivoted, being connected by a thin metal rod T with a diafragm D. In Fig. 3 the parts are shown in the position where pivoted reproducing lever L is moved upwardly from turntable TT of the phonograph, so that the reproducer is inoperative by the phonograph record but yet operable by the telephone receiver. The common diafragm D, although constructed of mica to be suitable as a telephone diafragm as well as a phonograph diafragm, is mounted in the ordinary fashion of phonograph diafrags, i. e., between rubber gaskets U. The reproducer is shown as of the usual construction, at R, provided with reproducer socket RS connected to tone arm TA. Soft iron armature A of the telephone receiver is pivoted at P², its lower end being supported by spring G. The arrangement of the polarizing magnet M is shown clearly. the entire telephone apparatus, including diafragm D, and also reproducing lever RL, being enclosed in a casing C having an opening X for the passage of lever RL, which carries at its outer end the needle-holder NH for needle N. Casing C is secured to sound reproducer R by suitable means such as screws E.

In Figs. 1 and 2 is shown another form, wherein common diafragm D may be of mica as in Fig. 3, the end of lever RL adjacent the center of the diafragm (to which it is connected by tie rod T) being in the form of or combined with an armature A for the telephone receiver,—the construction of which is of the type known as the Brandes. Otherwise the construction is as in Fig. 3, save that casing C enclosing the telephonic apparatus and

lever RL is secured to reproducer R by clips L (Fig. 2).

In the form of Figs. 1 and 2 as in the apparatus shown in the other figures, suitable binding posts BP may be provided as shown for the telephone windings. In Figs. 2 and 3, screws S are shown by which the polarizing magnet M is secured within casing C, such magnets suitably supporting the forms for telephone windings W¹ and W², the pole pieces (Figs. 1-2) O¹, O² of the windings being located adjacent armature A to co-operate therewith with respect to telephone diafragma D acting also as diafragma for the phonograph tone arm TA. Diafragma D is in any form of the invention designed suitably for operation with vacuum tube radio amplifying sets, as by being constructed of heavy mica or corrugated aluminum, so as to ensure sufficient intensity and good quality of sound, and to be adapted to produce vibrations of sufficient strength to render the operation of the phonographic tone arm by the radio set as effective as it is when operated mechanically by lever RL and needle N on the phonographic record.

By thus providing a diafragma suitably constructed and arranged to be operated by properly-disposed telephonic receiving apparatus, and to be operated as ordinarily in a phonograph by the record through lever RL, I provide an advantageous arrangement constituting a single permanent compact unit of sound producer, salable as a replacement part, which operates efficiently, is not expensive to manufacture, and dispenses with so-called "adapters" of various sorts for temporary combination of telephone receiver complete with its own diafragma, with the sound producer of the phonograph.

As shown in Figs. 1, 2 and 3, the unit comprises a casing C constructed to be connected with the tone arm TA of the phonograph, said casing housing the telephonic apparatus, the reproducing lever RL and the diafragma D common to them both, the reproducing lever being located between the telephonic apparatus and the common diagram, said lever extending out through casing C to needle holder NH and connected inside the casing to a central part of the diafragma D. The diafragma is supported at its periphery in the casing at the side thereof which is relatively close to the part of the casing which is constructed to be connected to tone arm TA, and the telephone apparatus is supported on the casing at another portion which is more remote from the tone arm; and means are provided in all cases whereby the winding of the telephonic receiving apparatus can operate the common diafragma independently of the reproducing lever.

I claim:—

A sound-reproducing apparatus comprising a sound box, a diafragma mounted on the sound box, a needle for operating the dia-

fragm under the control of a phonograph record, and electro-magnetic means connected with the sound box for operating the diafragma when the needle is out of contact with the phonograph record.
